UNITED STATES PATENT OFFICE.

THOMAS KEEPFER, OF PHILADELPHIA, PENNSYLVANIA.

ADJUSTABLE HANDHOLD FOR SAWS.

No. 834,622.

Specification of Letters Patent.

Patented Oct. 30, 1906.

Application filed April 6, 1906. Serial No. 310,215.

To all whom it may concern:

Be it known that I, THOMAS KEEPFER, a citizen of the United States, residing at the city of Philadelphia, in the county of Philadelphia and State of Pennsylvania, have invented certain new and useful Improvements in Adjustable Handholds for Saws, of which the following is a specification.

My invention relates to an adjustable handhold adapted to be applied to the handle of an ordinary saw to enable the saw to be readily used either right or left for sawing close to a vertical structure or wall without barking or abrading the knuckles of the hand in operating the saw or in other ordinary uses thereof.

The nature and characteristic features of my invention will be more fully understood from the following description, taken in connection with the accompanying drawings, forming part hereof, in which—

Figure 1 is a perspective view of a saw, showing a handhold embodying main features of my said invention detachably applied to an ordinary saw-handle. Fig. 2 is a side elevational view of a detachable handhold, and in dotted outline the saw-handle, with a handhold of my said invention clamped thereto. Fig. 3 is a side elevational view of the handhold; and Fig. 4 is a transverse sectional view on the line $x-x$ of Fig. 2, showing in detail the form of the flanged sleeves employed in conjunction with the handhold proper for detachably securing the handhold to any ordinary saw-handle for right or left hand work in proximity to a wall or other structure to part therefrom the projection of a board from the same.

Referring to the drawings, a is an ordinary saw provided with the usual wooden well-known type of handle a' . b is the handhold of my invention, which consists of preferably an arched hold b^1 , thickened about and from the middle and terminating at the respective ends in flanges b^2 and b^3 for bearing against the said handle a' , as shown in Fig. 2. Both ends of the handhold b are extended to form shanks or studs b^3 and b^4 , the interior of which

are hollow and the walls of which are threaded for a purpose to be presently explained. c and c' are the flanges of the sleeves c^2 and c^3 , fitting the shanks or studs b^3 and b^4 of the handhold b . In the openings c^4 and c^5 of the sleeves are inserted tightening screws or bolts d and d' for engaging the flanges c and c' to the saw-handle a' when the sleeves are tightened on the shanks or studs b^3 and b^4 , as clearly illustrated in Fig. 1. In sawing a board or other piece of material projecting from a wall or other structure by simply arranging the handhold so that it is in the position shown in Fig. 1 this may be readily accomplished or the handhold may be readily shifted into a reverse position to that shown by loosening the tightening screw bolts d and d' to permit the handhold b to occupy a position the opposite of that shown. By then tightening the bolts or screws d and d' in the sleeves c^2 and c^3 and studs or shanks b^3 and b^4 of the handhold b a left-hand sawing operation may be carried on without barking or abrading the knuckles of the hand.

Having thus described the nature and objects of my invention, what I claim as new, and desire to secure by Letters Patent, is—

1. The combination with a saw-handle, of a handhold provided with shanks or studs, sleeves fitting the shanks or studs and provided with projections or flanges, and means for securing the sleeves and flanges to said saw-handle.

2. The combination with a saw-handle, of a handhold provided with flanged ends and shanks, sleeves provided with flanges fitting the shanks and said flanges engaging the handle and means for securing the sleeves and flanges to said saw-handle.

In witness whereof I have hereunto set my signature in the presence of two subscribing witnesses.

THOMAS KEEPFER.
